UNITED STATES PATENT OFFICE.

GEORGE I. LEHMAN AND JULIUS PENSAK, OF BROOKLYN, NEW YORK.

REFERENCE CARD.

Application filed January 27, 1927. Serial No. 184,032.

This invention relates to new and useful improvements in cards, and more particularly to a reference card or index card upon which various items or other indicia may be written, printed or otherwise inscribed for reference purposes.

The primary object of the invention resides in providing a card having identification data upon its obverse face and provided with a pocket adapted to receive therein a separable slip, such as a metal, paper or cardboard strip, bearing upon its obverse surface co-relative data which is visible through a recess provided at the edge of the card and the mouth of the pocket and which is visible when the slip is inserted in the pocket.

A further object of the invention resides in constructing a card with a pocket preferably between the laminations or layers of which said card may be formed.

Still another object resides in constructing a card with a pocket provided adjacent one end thereof, the mouth of said pocket being at the edge of said card, and a still further object resides in cutting away the walls of the pocket at the mouth thereof in a manner which will permit a separable element to be readily and freely inserted or withdrawn from said pocket.

A still further object resides in providing a device which is simple and durable in construction, inexpensive to manufacture, efficient in use and capable of application to various uses.

With these and other objects in view, our invention consists in the novel features of construction, combination and arrangement of parts, as will be hereinafter referred to and more particularly pointed out in the specification and claims.

In the accompanying drawing forming a part of this application:

Figure 1 is a front elevation of a card constructed in accordance with our invention, the auxiliary element being shown removed from the pocket of the card;

Figure 2 is a transverse section as seen on the line 2-2 of Figure 1;

Figure 3 is an elevation of a blank in outspread position prior to formation of a modified form of the card; and

Figure 4 is a front elevation of a further modification of the invention.

In describing the invention, we shall refer to the drawing in which similar reference

characters designate corresponding parts throughout the several views and in which 1 designates a card of any preferred size or shape adapted for various purposes, such 60 as an index or reference card, the same being formed of two or more laminations or layers. Adjacent one end of said card and extending inwardly from one edge thereof, a 65 pocket 2 is formed by separating the layers or laminations. This pocket extends inwardly from the one edge of the card and may be of any desired width and length but preferably terminates short of the edge of the card opposed to that from which the 70 mouth of said pocket is formed.

As a reference card or the like, various data may be written, printed or otherwise inscribed thereon and we provide in connection with this card a strip 3 which may be 75 formed of paper, card board or metal which is adapted to be inserted and received in the pocket 2. This strip or auxiliary element is adapted to have data printed, written, impressed or otherwise inscribed thereon which 80 is co-related to the data contained on the face of the card 1. Thus, the auxiliary element 3 may at all times be carried in direct association with the card 1 to which it is 85 related.

One wall of the pocket 2 at the mouth thereof is cut away arcuately as shown by the numeral 4 and the other wall thereof is cut away to a greater extent arcuately as 90 shown by the numeral 5. The cut away portions of the walls enable the strip or element 3 to be readily grasped by the index finger and thumb and removed from the pocket and the cutting away of one wall to a lesser extent than the other provides obviously, a 95 backing or guide means to enable the strip or element 3 to be readily and quickly inserted in the pocket when desired.

As shown in Figures 1 and 2, the pocket 2 is formed by separating the laminations 100 or layers of the card 1 after the latter has been cut. A modified form of this invention is disclosed in Figure 3 wherein a blank or strip 6 is provided having its one edge adjacent one end cut away arcuately as 105 shown at 7. Correspondingly the last-mentioned edge of the blank adjacent the opposite end is cut away to a greater extent as shown at 8. This blank 6 is adapted to be folded along the dotted line 9 and the two 110 halves of the blank secured together on their inner opposed faces by means of an adhesive,

or otherwise as desired. Those portions of the two inner opposed faces of the folded elements of the blank extending inwardly from the cut-away portions 7 and 8 are not secured together and thus will permit the pocket to be formed between the folded elements.

A further modified form of the invention is disclosed in Figure 4 in which a card 10 is provided having applied to one face thereof adjacent its one end an outer pocket member 11. The mouth of the pocket is formed in the manner described and shown in connection with the other forms of the device. 15 Various other modifications of this invention may be provided.

From the foregoing description of the construction of our improved device, the manner of constructing and applying the 20 same to use will be readily understood.

It will be seen also that we have provided a simple, inexpensive and efficient means for carrying out the purposes of the invention and while we have particularly described the elements best adapted to perform the functions set forth, various changes 25

in form, proportion and in the minor details of construction may be resorted to, within the scope of the appended claim, without departing from the spirit or sacrificing any 30 of the principles of the invention.

What we claim is:

A card composed of confronting plies of material having juxtaposed surfaces intimately joined with each other over portions 35 of their areas and leaving disjoined portions of their areas forming a pocket leading in from the edge of the card, said card being provided with identification data appearing upon its obverse face, said card 40 having at its edge and at the mouth of the pocket a recess, and a slip adapted to enter said pocket and fill the same and having upon its obverse face identification data 45 corelative with the data upon the card, the data upon the slip being visible through the recess when the slip is enclosed in the pocket.

In testimony whereof we affix our signatures.

GEORGE I. LEHMAN.
JULIUS PENSAK.
